DESIGN FOR A COMBINED GRILLE, HOOD,
FENDERS, AND BUMPER FOR VEHICLES

Walter F. Rothe, Washington, D. C.

Application August 5, 1948, Serial No. 147,958

Term of patent 7 years

(Cl. D14—18)

To all whom it may concern:

Be it known that I, Walter F. Rothe, a citizen of the United States of America, residing in Washington, District of Columbia, have invented a new, original, and ornamental Design for a Combined Grille, Hood, Fenders, and Bumper for Vehicles, of which the following is a specification, reference being had to the accompanying drawing, forming part thereof.

Figure 1 is a front perspective view of a combined grille, hood, fenders, and bumper for vehicles, showing my new design.

Figure 2 is a side elevational view of the same.
Fig. 3 is a top plan view of the same.

I claim:

The ornamental design for a combined grille, hood, fenders, and bumper for vehicles, substantially as shown.

WALTER F. ROTHE.
